UNITED STATES PATENT OFFICE.

JOSEF MECERA, OF WASHINGTON, DISTRICT OF COLUMBIA.

KEYED ZITHER.

1,040,232.

Specification of Letters Patent.

Patented Oct. 1, 1912.

Application filed March 4, 1912. Serial No. 681,346.

To all whom it may concern:

Be it known that I, JOSEF MECERA, a citizen of the United States, residing at Washington, in the District of Columbia, have invented certain new and useful Improvements in Keyed Zithers; and I do declare the following to be a full, clear, and exact description of the invention, such as will enable others skilled in the art to which it appertains to make and use the same.

This invention relates to improvements in musical instruments.

One object of the invention is to produce a zither or like musical instrument having an improved construction and arrangement of key operated means for striking the strings.

Another object is to improve and simplify the action shown in my pending application for musical instruments Serial No. 671,642 filed January 17, 1912.

With these and other objects in view the invention consists of certain novel features of construction, and the combination and arrangement of parts as will be more fully described and claimed.

In the accompanying drawings; Figure 1 is a plan view of a zither or similar musical instrument embodying my invention; Fig. 2 is an enlarged vertical section of a portion of the instrument showing more clearly the construction and arrangement of the hammer action; Fig. 3 is an enlarged plan view of a portion of the action as shown in Fig. 2, parts being broken away to more clearly illustrate the relative position and arrangement of the inner ends of the keys and the string engaging hammers; Fig. 4 is an enlarged detail perspective view of one of the hammers of the action; Fig. 5 is a similar view of the inner end of one of the keys.

My improved musical instrument is illustrated herewith in the form of a zither having a frame 1 in the rear portion of which is suitably arranged a sounding board 2. Arranged above and stretched across the board 2 are the strings 3 of the instrument. The strings 3 are attached at their ends to suitable tuning pins 4 on which the strings may be wound to impart the proper tension thereto. The strings pass over suitable bridges 5 secured in the frame of the sounding board as shown. The back board 6 carries a hood 7 which covers the inner portion of the action and adjacent to the forward edge of the sounding board 2 is a key

supporting bar 8 on which are loosely pivoted a series of keys 9. The keys 9 are pivotally connected to the bar 8 to swing or rock in a vertical plane when the outer ends thereof are depressed, said pivotal connection comprising pivot screws 10 which are passed upwardly through tapered passages 11 in the bar 8 and have their ends screwed into the lower side of the keys as clearly shown in Fig. 2 of the drawing. Between the heads of the screws and the lower side of the bar 8 are arranged felt washers 12, while similar washers 13 are arranged on the screws between the upper sides of the bar 8 and the adjacent lower sides of the keys, said washers forming a yielding connection between the parts with which they are engaged and also preventing any noise which might occur from the engagement of said parts. The lower outer edge of the hood 7 is bent or turned inwardly to form a flange 14 on the lower side of which is secured a felt cushioning strip 15 which may be engaged by the upper sides of the keys 9 when in their normal positions and which prevents any noise that might be occasioned by the keys striking the flange 14 of the hood.

Under the hood 7 above the keys and a slight distance in front of the pivotal connection thereof is a transversely disposed stop bar 16, the ends of which are suitably secured to the ends of the hood. In the bar 16 is arranged a series of stop screws 17 which are engaged by the adjacent portions of the keys when the latter are released and which limit the downward movement of the inner ends of the keys. By adjusting the screws 17 the movement of the keys may be regulated. The keys are restored to their normal positions after being struck by means of short coiled springs 18, the upper ends of which are secured to the lower sides of the keys, while their lower ends are secured to pins 19 arranged in the rear side of the key supporting bar 8. The rear or inner ends of the keys are notched or recessed to form at their lower edges longitudinal rearwardly extending trip fingers 20, the outer ends of which are slightly beveled and rounded as shown.

Arranged above the strings 3 and adjacent to the inner ends of the keys are a series of string engaging hammers, said hammers being preferably in the form of blocks 21, which are secured to the forward ends

of short hammer supporting springs 22 the opposite ends of which are secured to a cleat 23 arranged on the adjacent side of the back board 6 as shown. Between the upper edges 5 of the hammer blocks 21 and the adjacent ends of the springs are felt cushioning strips 24 the outer ends of which overhang and cover the adjacent upper corners of the hammer blocks. The hammer blocks 21 are notched or recessed from their lower edges 10 upwardly for a suitable distance as shown at 25 to provide trip lugs 26 which are adapted to be engaged by the trip fingers 20 on the inner ends of the keys. The outer ends of the lugs 26 are beveled or inclined 15 from their lower edges upwardly and rearwardly as shown at 27. Arranged above the hammer supporting springs 22 and spaced a suitable distance therefrom is a stop strip 28 the ends of which are secured in any suitable manner to the ends of the hood 7. In the strips 28 above each of the springs 22 is arranged a stop screw 29, said screw being provided to limit the movement and to 25 regulate the resistance and force of the springs 22. On the upper side of each of the springs 22 is arranged a felt cushioning strip or pad 30 which prevents the spring from coming into direct contact with the 30 lower end of the screw 29.

By constructing and arranging the keys and hammers of the instrument as herein shown and described, it will be seen that when the outer ends of the keys are depressed, their inner ends will be raised thereby bringing the trip fingers 20 on said inner ends of the keys into engagement with the outer edges of the lugs 26 of the hammers. The hammers when thus engaged by the trip 35 fingers 20 will be lifted or sprung upwardly to a sufficient distance to permit the ends of the fingers to disengage or slip over the ends of the lugs 26 whereupon the springs 22 will bring the hammers back into forcible engagement with the strings 3, thus sounding 40 the latter. As soon as the outer ends of the keys are released the springs 18 thereof will swing the inner ends of the keys downwardly thus restoring the latter to their normal positions. When being thus 45 swung downwardly the rounded ends of the fingers 20 on the inner ends of the keys will engage the beveled or inclined ends 27 of the lugs 26 and will by depressing the hammers 21 to a slight extent, pass said beveled ends of the lugs 26 as will be readily understood. The ends of the fingers 20 in coming 50 down on the beveled ends of the lugs 26 first engage the overhanging ends of the felt strips 24 on the upper edges of the hammer heads, said felt strips thus preventing any noise which might be occasioned from the engagement of the fingers 20 with the ends 55 of the lugs 26.

60 In connection with the action just de-

scribed, I also preferably provide means for quickly tuning the instrument, said means comprising a fret bar 31 which is arranged across a portion of the strings as shown in Fig. 1 of the drawings and which is secured to the sounding board in any suitable manner and adapted to be drawn down onto the strings, obliquely across the same as shown in Fig. 1. Assuming that all of these strings at the right end of the instrument were 70 tuned to a certain tone, which any amateur could do, then when the fret bar 31 is clamped down onto them, their tone is immediately changed to the pitch which the higher strings of the finished instrument 75 will require, and without necessitating any great amount of exactitude in the act of tuning the instrument.

From the foregoing description taken in connection with the accompanying drawings, the construction and operation of the invention will be readily understood without requiring a more extended explanation.

Various changes in the form, proportion and the minor details of construction may 80 be resorted to without departing from the principle or sacrificing any of the advantages of the invention as claimed.

Having thus described my invention, what I claim is;

1. A hammer action for musical instruments comprising the hammer having a trip lug projecting from its outer end and beveled inwardly on its outer extremity, a cushioning strip secured upon the hammer and projecting over the beveled end of its lug, means for yieldingly supporting the hammer above a string, and a pivoted key having a finger at its inner end adapted to contact with the under side of the lug on its ascent and to contact with the strip and then move over the beveled extremity of said lug on its return.

2. In a hammer action for musical instruments, the combination with a substantially horizontal leaf spring supported at one end, the hammer carried by the other end of the spring and having a lug projecting from it and beveled on its extremity, and a stop adjustable above the spring; of a key lever pivoted between its ends and having a finger projecting from its inner extremity and adapted to engage said lug as the finger rises when the other end of the key lever is depressed, and a spring holding the finger-end of said lever normally upward.

3. In a keyed zither, a frame, a sounding board, the strings, a series of keys pivotally mounted in said frame and having trip fingers at their inner ends, a series of spring-supported hammers having beveled outer ends adapted to be engaged by the rising trip fingers when the keys are depressed, cushioning strips secured on said hammers and overlying their ends in position to be

engaged by the descending trip fingers on the return stroke of the keys, a stop bar above the hammer-supporting springs, and adjusting screws in said bar for limiting 5 their rise.

4. In a musical instrument, a frame, a sounding board arranged therein, strings arranged across said board, a series of keys pivotally mounted in said frame, trip fingers on the inner ends of said keys, said fingers having their ends beveled and rounded, a series of string-engaging hammers, springs to support said hammers in position over said strings, trip lugs on the outer 10 ends of said hammers, said lugs having beveled and rounded outer ends adapted to be engaged by the beveled rounded ends of the trip fingers on said keys whereby, when the keys are depressed, said fingers will engage 15 the lugs on said hammers and swing the latter upwardly against the pressure of their supporting springs and whereby when said fingers have swung said hammers upwardly 20

to a sufficient distance to pass said lugs said springs will bring the hammers down into 25 forcible engagement with said strings thus sounding the latter, cushioning strips arranged on said hammers in position to be engaged by the trip fingers of the keys in passing the trip lugs on the hammers on the 30 return stroke of the keys, a stop bar arranged above said hammer supporting springs, spring-adjusting screws arranged in said bar whereby the force of the springs is regulated, cushioning strips arranged between said springs and said screws, and a hood arranged over said hammers and the 35 inner portions of the keys.

In testimony whereof I have hereunto set my hand in presence of two subscribing 40 witnesses.

JOSEF MECERA.
